The ornamental design for a keyless entry remote, as shown.

DESCRIPTION

This application is related to co-pending U.S. patent application Ser. Nos. 29/419,225, 29/419,228, 29/419,229, and 29/419,230, entitled "Keyless Entry Remote". These applications have the same assignee as the present application. The above-identified applications are incorporated herein by reference.

FIG. 1 is a perspective view of a keyless entry remote showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
